(57) **CLAIM**

The ornamental design for a speaker system, as shown and described.

DESCRIPTION

FIG. 1 is a front perspective view of a speaker system according to the design;

FIG. 2 is a rear perspective view thereof;

FIG. 3 is a top plan view thereof;

FIG. 4 is a bottom plan view thereof;

FIG. 5 is a front elevational view thereof;

FIG. 6 is a rear elevational view thereof showing an alternate position of the design; and,

FIG. 7 is a right side elevational view thereof, the left side being a mirror view thereof.
